TABLE

Andrew Roth, Chicago, Ill., assignor to Kuehne
Manufacturing Co., Mattoon, Ill., a corporation
of Illinois

Application August 19, 1953, Serial No. 26,514

Term of patent 3½ years

(Cl. D33—14)

To all whom it may concern:

Be it known that I, Andrew Roth, a citizen of the United States of America, residing at Chicago, in the county of Cook and State of Illinois, have invented a new, original, and ornamental Design for a Table, of which the following is a specification, reference being had to the accompanying drawing, forming part thereof.

Fig. 1 is a perspective view of a table showing my new design.

Figs. 2, 3 and 4 are side elevational, end elevational, and bottom plan views, respectively, of the table leg element thereof.

The dominant features of my design reside in the portions shown in full lines.

I claim:

The ornamental design for a table, as shown and described.

ANDREW ROTH.
